FLUID-METER STRUCTURE

Frederick W. Hanks, Cleveland, Ohio

Application October 25, 1937, Serial No. 170,798

3 Claims. (Cl. 73—277)

This invention relates to fluid-meters, and more particularly meters such as are subject to exposure to freezing conditions; and it is among the objects of the invention to provide a construction minimizing damage and facilitating and accelerating reconditioning of a meter, and with minimization of waste from breakage.

To the accomplishment of the foregoing and related ends, the invention, then, comprises the features hereinafter fully described, and particularly pointed out in the claims, the following description and the annexed drawing setting forth in detail certain illustrative embodiments of the invention, these being indicative however, of but a few of the various ways in which the principle of the invention may be employed.

In said annexed drawing:

Fig. 1 is a side elevational view, partly in section, showing an embodiment of the invention; Fig. 2 is an enlarged fragmentary detail; Fig. 3 is an inverse plan of one of the elements; Fig. 4 is a bottom plan view showing a modification; and Figs. 5 and 6 are detail side elevations of other modifications.

Referring more particularly to the drawing, there is shown a meter housing 2, whose detail may vary, provision being had for suitable metering elements and a fluid chamber with inlet and outlet connections, one of which is indicated at 3. The housing has an opening, to be closed by a separable closure plate 4, and advantageously this may seat against a gasket 5. Projecting laterally from the housing outside the closure plate are bolting flange means or lugs 6. Conveniently there may be four lugs, spaced at intervals, although a larger or smaller number may be employed as desired. The form of closure plate illustrated in Fig. 1 embodies one or more projecting lugs 7, to mate under a corresponding lug 6 of the housing, and if the closure plate lugs are of a character to be frangible or breakable in the event of a freeze-up, such lugs may be availed of to the extent desired, being held by bolt-means 8, which may be a nut and bolt assembly or a cap screw if desired in some instances. As illustrated further in Fig. 1, the closure plate lug at the left has been broken off in a previous occurrence of damage, and it is here shown how such a mutilated and otherwise ordinarily discarded plate is quickly put back into service, a pressure member or L lever 10 being arranged to rest with one end on the housing lugs 6 and the other end on the closure plate. If the lug-engaging end 11 be a short upstanding leg, and the other portion be a relatively longer

leg extending beyond the periphery of the closure plate with the end 12 resting against the closure plate at a point adjacent the center, a lever action is had, the bolt-means 13 joining between the housing lug 6 and the member 10. Ordinarily, a nut and bolt combination is desirable, although a cap screw may be used in some instances. It is advantageous to provide a weakening groove 14 intermediary in the long leg of the pressure member, and thereby in the event of freeze-up, breakage at a predetermined zone may occur, and avoid more extensive damage. It will be observed that the pressure member where having angularly-directed legs 11, 12, constitutes with the bolt-means an L-lever system giving firm holding of the closure plate, together with particular convenience in the utilization and assembly, and closure plates with one or more original lugs still intact may be employed or closure plates in which all of the lugs have been broken off. Particular economies in usage of plates otherwise junk, are thus had. Similarly, as illustrated more particularly in Fig. 4, a form of a closure plate 4a without any lugs at all may be equally well employed, the pressure members 10 being applied on the housing lugs 6 and the closure plate 4a, as already indicated. A notable feature here also in contrast to prior bottoms with frangible lugs, is the possibility of forming the bottom plate of a non-corrodible metal, as for instance brass, etc., and the nuisance of rust-formation is obviated.

The manner of usage of the construction is already clear from the foregoing. A closure plate 4a, Fig. 4 formed without lugs, and assembled with the meter housing, is tightened into position with a set of pressure members 10 bolting to the housing lugs 6. Similarly, a closure plate 4, Fig. 1, which has lost one or more of its initially formed lugs in prior freeze-ups, is assembled with the meter housing 2 with bolt-means 8 to such of its lugs as are left, and with the pressure members 10 for the remainder. And when all of the original lugs 7 of the closure plate are broken off, the closure plate may still go on in service, with a full complement of the pressure members 10. Not only thus is the matter of getting it back immediately into service greatly expedited and simplified, but the expense and waste in parts heretofore junked on damage, is particularly advantageously controlled. If anti-slip means or roughening be provided on the lever or pressure members, an assured grip may be had under all conditions. Roughening or serrations 15 may be formed on the members. In

some cases where desired, an exaggerated biting portion 16 may be provided on the housing-engaging leg (Fig. 5), to seize into the opposing metal sufficiently to obviate possibility of slipping. The member 18 again may have a weakening groove 14b to localize breakage. By forming the pressure member with an offset, Fig. 6, the housing-engaging leg 16c may cooperate with the housing portion 6 as described, optionally a biting portion 16c being included, and several advantageous functions result together, in that the closure-engaging leg thus sets at such an angle as to be adjustable over the wide range of possible different forms of closure plate and the locus fracture is particularly well localized in the recess or groove 14c. Again, roughening or serrations may be provided on the closure-engaging leg.

Where the closure plate is of circular or lug-less periphery character, as plate 4a, Fig. 4, as a further refinement of the invention I may provide a lug 18 standing out from the plate. This affords a hold for gripping by a vise or wrench to loosen the plate in removal where there is obstinate sticking of the gasket.

Other modes of applying the principle of the invention may be employed, change being made as regards the details described, provided the features stated in any of the following claims, or the equivalent of such, be employed.

I therefore particularly point out and distinctly claim as my invention:

1. In fluid-meter construction, a housing, a separable closure plate having a body and a housing-engaging peripheral portion, and lever-means

for supporting said closure plate internally of its housing-engaging peripheral portion, said means comprising an L-lever having a long leg bridging beyond said housing-engaging peripheral portion to bear against the body of the closure plate internally of its housing-engaging peripheral portion and a short upstanding leg bearing against the housing lug, and bolt means for joining the lever and lug. 5

2. In fluid-meter construction, a housing, a separable closure plate having a body and a housing-engaging peripheral portion, and lever-means for supporting said closure plate internally of its housing-engaging peripheral portion, said means comprising an L-lever having a long leg bridging beyond said housing-engaging peripheral portion to bear against the body of the closure plate internally of its housing-engaging peripheral portion and a short upstanding leg having a biting portion to bear against the housing lug, and bolt means for joining the lever and lug. 10 20

3. In fluid-meter construction, a housing, a separable closure plate having a body and a housing-engaging peripheral portion, and lever-means for supporting said closure plate internally of its housing-engaging peripheral portion, said means comprising an L-lever having a long leg with an offset and bridging beyond said housing-engaging peripheral portion to bear against the body of the closure plate internally of its housing-engaging peripheral portion and a short upstanding leg bearing against the housing lug, and bolt means for joining the lever and lug. 25 30
